ELECTROADHESION APPARATUS

Knud Rahbek, Copenhagen, Denmark

Application November 3, 1932, Serial No. 641,030
In Denmark November 10, 1931

9 Claims. (Cl. 179—108)

This invention relates to a method and apparatus utilizing the electrostatic attraction or electro-adhesion produced by the passage of electric current through contacting surfaces of a semiconductor in contact with a semiconductor or a conductor.

From prior patents, particularly U. S. Patents No. 1,533,757, and No. 1,446,748, it is known that certain substances, called semiconductors, for example agate, slate, certain kinds of wood and paper, gelatine etc. exert a considerable attraction mutually or to conducting bodies in contact therewith, when a suitable electric current is directed through the surfaces of contact. The attraction depends on the potential drop produced by the flow of current through the contacting surfaces, and increases greatly with increasing voltage. The attraction is moreover accompanied by a frictional resistance of proportional magnitude, which tends to prevent relative displacement of the two surfaces.

Attempts have been made to utilize this effect in the technical arts in various ways such as by employing the electrostatic attraction or electro-adhesion produced at the contacting surfaces for moving one of the parts of the device towards the other one. Electroscopes, relays or other devices may be constructed on this principle. It has also been attempted, by moving mechanically the parts of the device, relatively to one another, and in such a manner that they were constantly in contact along a portion of their surfaces, to utilize the varying friction developed therebetween for the construction of electromechanical devices. In this way and by the use of a very small current (a fractional part of a milliampere) it is possible to release considerable mechanical tractive forces. This effect is readily obtainable by constructing one of the contacting members in the form of a rotary cylinder or disk, the other contacting member having the shape of a band or disk maintained in contact with the rotary member by means of a resilient force or otherwise.

Such devices would appear to be of utility in the construction of simple and cheap telegraph, telephone, oscillograph and other apparatus. These compared to known constructions for similar purposes would have the very considerable advantage that the activating mechanical forces need not be furnished by electric currents, but could be provided by a motor, a clockwork or the like, while the electric current required for governing these forces would remain quite small.

While the technical uses based upon this prin-

ciple appeared at the outset to possess great possibilities, experience in the laboratory has revealed important practical difficulties in that the electro-adhesion apparatus employed altered its properties during operation for relatively short periods (hours or days). Especially the active surfaces were altered to such an extent that the attracting force, on which the entire usefulness is based, either decreased considerably or became extraordinarily great, and in either case the practical utility of the device was destroyed.

Attempts were made to remedy this drawback by a special treatment of the surfaces with cleaning means, partly of mechanical and partly of chemical nature, but all attempts to devise constructions adapted to operate successfully for longer periods were frustrated.

Continued experiments and researches of the conditions here referred to have now shown that the change undergone by the devices in consequence of the passage of the current must be assumed to be due to electrochemical alterations.

The present invention has for its object to avoid the occurrence of electrochemical alterations in the device owing to the passage of the current, in such a manner that the device will retain the properties of value to the uses concerned, and the practical usefulness will be secured.

According to the invention this object is attained by passing only alternating current through the device, and in such a manner that any surplus of electrochemical action in one or the other direction will be avoided entirely. Practical experiments have shown that for attaining this result it is not sufficient merely to use alternating current, but it will be necessary to secure such a wave shape for the alternating current that the changing electrochemical effects originating from the positive and the negative impulses will counterbalance one another entirely. This result can be attained in several manners.

In the drawing:

Figs. 1, 2, 4, 6 and 8-10 show diagrammatically various arrangements and circuits for obtaining the desired mode of operation in accordance with the present invention, while:

Figs. 3, 5 and 7 illustrate characteristics of current curves showing the wave shape resulting from operation with the arrangement of Figs. 2, 4 and 6.

Fig. 1 shows a circuit arrangement for preventing a device consisting of a semiconductor 1 and a metal ribbon 2 disposed thereon from being altered by electro-chemical changes due to 55

the passage of the electric current. To this end, there is inserted in the connecting wires between the electro-adhesion device 1, 2 and an alternating-current generator 3, a condenser 4 of sufficiently high insulating resistance, for instance a mica condenser. The condenser 4 prevents the passage of direct current, which might otherwise be produced as a result of the inherent rectifying tendency of the device and the more or less generally occurring asymmetrical shape of the alternating-current wave.

In fact any method that prevents direct current from passing through the device may be employed. This result may for instance also be attained by utilization of a suitable wave shape for the alternating current. The varying voltage, however, involves a use of a varying tractive force and frictional effect between the contacting surfaces of the device. If it is desired to equalize the pulsating tractive force thereby produced, various methods may be used, and some of these will be mentioned by way of example in the following.

The arrangement shown in Fig. 2 employs a rotary commutator device 5, which has for its object to convert into alternating current the direct current otherwise derived from the direct-current source 6. From the commutator an alternating-current voltage V may be taken, the curve of which has the angular shape shown in Fig. 3. A voltage of this shape gives a tractive force which is very nearly as uniform as that obtained with direct current.

Fig. 4 shows an arrangement in which the device 1, 2 is used as a part of a loud-speaker, the ribbon 2 actuating a sound-producer 19. In order to prevent the polarizing voltage on the device 1, 2 required for the operation of the apparatus from producing permanent electrochemical changes therein, a current-reversing device is inserted, which consists of a switch having a resilient arm 20 adapted to swing between two contacts 21, 22 in the circuit connecting the device with the polarizing battery 8. The arm 20 can be moved by a cam disk 23 in connection with a spring 24. Fig. 5 shows the shape of curve for the polarizing voltage V attained with this arrangement. By adjustment of the battery connection 25 and by alteration of the shape of the cam disk 23, the amplitude as well as the duration of the oppositely poled voltage impulses can be varied.

In the arrangement shown in Fig. 6, the electro-adhesion device 1, 2 is connected to a potentiometer 7 inserted in a circuit which contains a series resistance 8, a glow discharge valve 9 arranged in parallel to the potentiometer 7, and the secondary of a transformer 10 supplied with current from an alternating current generator 11. The discharge valve 9, when lighted, will produce a drop of voltage in the series resistance, and will itself remain at a voltage situated in the vicinity of the lighting voltage, whereby for the alternating voltage V impressed upon the device 1, 2 will have the angular wave shape shown by full lines in Fig. 7, the dotted wave tops V' indicating the alternating voltage of the generator, and the voltage V'' indicating the glow discharge voltage of the valve, or a fractional part thereof determined by the adjustment of the potentiometer. With such a shape of curve the attracting force produced between the parts of the device is essentially more uniform than with a pure sinusoidal voltage.

By the use of poly-phase currents there results

a considerable equalization of the tractive force and, thereby, considerably increased attraction and frictional forces between the parts of the device. Fig. 8 shows by way of example a device in which a two-phase alternating current is used, the phases of which are mutually displaced by 90° . From a transformer 12 the current is directed to suitably proportioned serially connected condenser 13 and resistance 14, whereby in the manner known per se two voltages of equal magnitude but phase-displaced by 90° relatively to one another are obtained. These voltages are supplied respectively to the upper and lower portions of the device 1, 2, which, in the example shown, consists of a semiconductor 1 and two conductors 2 disposed on an insulating supporting plate 15 and connected, separately through condensers 4, to the circuit consisting of the transformer 12, the condenser 13 and the resistance 14.

Fig. 9 shows a device in which three metal strips 20 disposed on an insulating supporting plate 16 form one part of the device, while the other part consists of a semiconductor 1. The three metal strips are connected respectively through condenser 4 to individual phases of a Y-connected three-phase alternating-current generator, having its neutral or return lead connected to conductor 1. The attractions between the metal strips and the semiconductor will be greatly equalized by this construction, due to their phase displacements which are such that as the tractive force at one strip decreases, it increases at others.

If it is desired, by means of the frictional force produced in the device, to cause a diaphragm or recording pen or the like to move synchronously with the alternating voltage, it may be of advantage to use a two-phase current and to omit the resilient counterforce ordinarily used. For instance a toning sound-reproducer may be constructed as shown in Fig. 10. Two phase-displaced voltages produced in the manner described in connection with Fig. 8, are supplied respectively to the devices 1, 2 employing cylindrical semiconductors, adapted to rotate in opposite directions as indicated by arrows 17. Over the cylinders 1 metal ribbons 2 are disposed, which are connected respectively to opposite sides of a diaphragm 18. As the voltage, and consequently also the attraction, is maximum in one of the devices when it is zero in the other one, the two metal ribbons 2 will move the diaphragm now to one and now to the other side in synchronism with the alternating current, and the membrane will produce a tone, the frequency of which is twice as high as the number of periods of the alternating current.

I claim:

1. In a device utilizing electro-adhesion between contacting surfaces of substances traversable by electric current, the method of operation which comprises, passing through said surfaces an alternating current of angular wave shape thereby to minimize fluctuations in the resulting tractive forces between said surfaces while preventing the occurrence of permanent electrochemical alterations in said device.

2. In a device utilizing electro-adhesion between contacting surfaces of substances traversable by electric current, the method of operation which comprises, passing through said surfaces an alternating current of substantially rectangular wave shape thereby to minimize fluctuations in the resulting tractive forces between said surfaces while preventing the occurrence of permanent electrochemical alterations in said device.

3. In an electro-adhesion device including conductive bodies having surfaces in contact, a source of alternating voltage connected to said bodies and means adapted to prevent the flow of detrimental direct current through said bodies.
4. In an electro-adhesion system including conductive substances having surfaces in contact, a source of alternating voltage, a connection for applying said voltage to said device, and a condenser serially interposed in said connection.
5. In an electro-adhesion system according to claim 3, the alternating voltage applied being of angular wave shape.
6. An electro-adhesion system comprising a first conductive element having a surface arranged to contact simultaneously with surfaces of a plurality of conductive elements mounted in insulated relation, a poly-phase voltage source having a common return, and connections extending respectively from said common return to said first conductive element and from individual phases of said source to said elements insulatedly mounted.
7. An electro-adhesion system according to claim 6 wherein condensers are interposed in said connections from said individual phases.
8. In an electro-adhesion device adapted to be controlled by varying electric currents and comprising at least two bodies of substances traversable by said currents and contacting each other, means for applying an alternating current besides the controlling current to said bodies, said alternating current being of other than ordinary sinusoidal shape and its positive half-waves being adapted to extinguish any electrochemical effect of its negative half-waves, and vice versa.
9. In an electro-adhesion device adapted to be controlled by varying electric currents and comprising at least two bodies of substances traversable by said currents and contacting each other, means for applying an alternating current besides the controlling current to said bodies, said alternating current being of other than ordinary sinusoidal shape and its positive and negative half-waves being essentially symmetrical.
